UNITED STATES PATENT OFFICE.

MANGO TANI, OF CONEY ISLAND, NEW YORK.

CLEANING MATERIAL.

Specification of Letters Patent. Patented Feb. 14, 1922.

1,406,243.

No Drawing.

Application filed August 19, 1920. Serial No. 404,709.

To all whom it may concern:

Be it known that I, MANGO TANI, a subject of the Emperor of Japan, and resident of Coney Island, in the county of Kings and State of New York, have invented certain new and useful Cleaning Material, of which the following is a specification.

My invention relates to cleaners, and, particularly, to cleaning material for the hair and scalp.

It consists, preferably, of a comminuted form or sea weed, or sea moss, grown in Japan, called "Funori," either in powder form or in solution.

This sea weed, or sea moss, has peculiar cleaning qualities, and when used to clean the hair, it leaves the hair glossy and free of foreign matter.

The Funori should be gathered, preferably, while young and tender, which happens at certain seasons of the year, and should be finely granulated or comminuted.

To use it, the powder is mixed, perhaps a teaspoonful to a glass, for example, in hot water, which quickly dissolves it. It is then applied to the hair or other parts to be cleansed, and then rinsed out with warm or cold water. Applied to the hands, the skin is rendered soft and white. Other objects may be cleaned by Funori.

What I claim is—

A cleansing composition for topical application comprising comminuted *Gloioptilis furcata*.

MANGO TANI.
